UNITED STATES PATENT OFFICE.

JULIUS J. ZIELENSKE, OF CHICAGO, ILLINOIS.

ATTACHMENT FOR WASHBOILERS.

1,197,249.

Specification of Letters Patent. Patented Sept. 5, 1916.

Application filed May 11, 1916. Serial No. 96,850.

To all whom it may concern:

Be it known that I, JULIUS J. ZIELENSKE, a citizen of the United States, residing at Chicago, in the county of Cook and State of Illinois, have invented new and useful Improvements in Attachments for Washboilers, of which the following is a specification.

This invention relates to attachments for domestic wash boilers and has as its object to provide an attachment which may be readily applied to any ordinary wash boiler and which will add to the efficiency of the same by assisting the circulation of the water through the articles being washed.

It is one aim of the invention to provide an attachment of the class described so constructed that the hot water from the vicinity of the bottom of the boiler will be conveyed to the top of the boiler and sprayed over the surface with sufficient force to permeate the articles of clothing at the surface of the water, the rapidity of flow of the circulating water currents being at the same time increased so as to provide for thorough cleansing of the articles.

It is another aim of the invention to provide an attachment of the class described so constructed that the major portion thereof, or in other words that portion through which the water is caused to circulate, may be removed without disturbing the remainder of the structure so that the said portion of the attachment may be cleaned after use.

In the accompanying drawings, Figure 1 is a top plan view of the device, Fig. 2 is a vertical longitudinal sectional view therethrough, Fig. 3 is a bottom plan view of the cap member of the device removed from the remainder of the structure.

The attachment of the present invention embodies a hollow base portion which constitutes a hot water receiving chamber and which comprises a top 5 which is preferably substantially elliptical in marginal outline and which is inclined upwardly from its margin to its central portion as clearly shown in Fig. 2 of the drawings. The top 5 is imperforate and is provided with a depending marginal flange 6 which is formed with a circumscribing series of openings 7 through which water may enter the said chamber. The chamber itself is open at its bottom, and when the attachment is disposed within the boiler, the lower edge of the flange 6 rests upon the upper surface of the bottom of the boiler, indicated by the

numeral 8. For a purpose to be presently explained, the chamber is provided interiorly with two or more baffles 9 which, in the present instance, are secured at their upper edges to the under side of the top 5 of the chamber, the lower edges of the baffles resting upon the upper side of the boiler bottom, and the baffles being preferably longitudinally arcuate and arranged each inwardly of one end of the said body.

Upstanding from the central portion of the top of the hot water receiving chamber is a water conducting tube 10 which communicates at its lower end with the interior of the said chamber and which, at its upper end, is flared as at 11. Disposed upon the open flared upper end of the tube 10 is a concavo-convex cap 12, the cap being arranged with its concave side presented downwardly and being formed on this side with a plurality of radial ribs 13 which rest at their lower edges upon the upper edge of the said tube, and which serve to slightly space the under side of the cap from the said edge of the tube to provide water outlet passages 14 located inwardly of the edge of the cap.

In order that the several parts comprising the attachment may be held properly assembled with each other and with the bottom of the wash boiler, a means is provided which will now be described.

A rod 15 is threaded at its lower end into an upstanding neck 16 formed upon the upper side of a head 17, the said neck being fitted through an opening formed centrally in the boiler bottom 8, and a washer 18 preferably of tin is fitted to the said neck 16 and bears between the head 17 and the under side of the boiler bottom. The neck 16 is exteriorly threaded and has fitted thereon a rubber packing washer 19 and a nut 20, which latter is tightened upon the neck so as to bear firmly against the washer 19 and prevent leakage of water through the opening which receives the neck 16. The rod 15 extends upwardly axially of the tube 10 and through an opening 21 formed through the thickened mid-portion 22 of the cap 12. The upper end of the rod is threaded as indicated at 23, and fitted thereto is a wing nut 24 which bears upon the upper side of the said cap.

From the foregoing description of the invention it will be understood that the hot water at the bottom of the boiler will enter

the water receiving chamber through the openings 7 and that a circulation will be created within the chamber by reason of the presence of the baffles 9. The water, upon rising through the tube 10, will be forcibly ejected through the passages 14 in the form of a sheet or spray onto the surface of the body of water and the articles at the said surface. After the device has been used and it is desired to clean the same, the wing nut 24 may be removed and the entire device, including the rod 15 and the parts associated with the lower end thereof, may be removed.

15 I claim:

1. In an attachment of the class described, a water receiving chamber, provided with water inlet openings, a water conducting tube extending upwardly from the said chamber and in communication therewith, a cap disposed upon the upper end of the said tube and provided with a concave under side

having ribs resting upon the edge of the said upper end of the tube, the ribs spacing the said under side of the cap from the said end 25 of the tube, and means connected with the cap for holding the same upon the tube and for securing the attachment to the bottom of a vessel within which it is to be arranged.

2. In an attachment of the class described, 30 a water receiving chamber provided with water inlet openings, a water conducting tube extending upwardly from said chamber and in communication therewith, a cap over the upper end of said tube and having 35 ribs on its under side resting on the edge of said upper end of the tube, said ribs spacing the under side of the cap from said end of the tube, a rod connected to the cap and passing through the tube, and means for securing the rod to the bottom of a vessel within which the attachment is located.

In testimony whereof I affix my signature.
JULIUS J. ZIELENSKE.
